(57) **CLAIM**

The ornamental design for a woodworking ruler, as shown and described.

DESCRIPTION

FIG. 1 is a perspective view of a woodworking ruler showing new design, wherein the sliding head is disposed at one location on the body of the woodworking ruler.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is a perspective view thereof, wherein the sliding head is disposed at another location on the body of the woodworking ruler.
